UNITED STATES PATENT OFFICE.

WILLIAM C. INGRAM, OF GRAND RAPIDS, MICHIGAN.

STREET-FLUSHING MACHINE.

1,216,455.

Specification of Letters Patent. Patented Feb. 20, 1917.

Application filed December 3, 1915. Serial No. 64,793.

To all whom it may concern:

Be it known that I, WILLIAM C. INGRAM, a citizen of the United States, residing at Grand Rapids, in the county of Kent and State of Michigan, have invented new and useful Improvements in Street-Flushing Machines, of which the following is a specification.

My present invention relates to street flushing machines, and its object is to provide a machine of that character in which the water shall be discharged with little friction or obstruction in its flow through the pipes.

This object is attained by, and the invention finds preferable embodiment in, the machine hereinafter described and illustrated in the accompanying drawings, in which:—

Figure 1 is a side view of a street springing and flushing machine;

Fig. 2 is a top plan view of a discharge pipe of such a machine, and adjacent parts;

Fig. 3 is a cross section of such pipe;

Fig. 4 is a longitudinal section of a portion of the same, the line of section passing through a vent, and

Fig. 5 is a view in perspective of said discharge pipe.

The water tank 1 is carried on the vehicle wheels 2, on a suitable frame 10, and by suitable conduits 3 the water therein flows to the horizontal flushing discharge pipe 4. This pipe is provided at its forward side with vents 5 through its wall whereby the water is discharged upon the surface of the street. In order that the water may with little friction or obstruction flow from the conduits, through the discharge pipe and out of the vents, this discharge pipe is formed approximately ovate in cross-section as particularly shown in Fig. 3. In passing from the conduits, the body of the stream flows along the larger—the rear—portion 6 of the pipe; and those portions of such stream as are discharged through the several vents turn forwardly toward and through the vents, passing between portions 7 of the pipe's inner surface near the vents and on opposite sides thereof, which portions 7 con-

verge more closely to parallelism than those portions of the pipe's inner surface which are more remote from the vents, *i. e.* the rear-portion of the pipe. By such convergence of the portions 7, the water is so directed through the vents as to impart to each jet a forceful or flushing effect, and yet the flow of the body of the stream through the larger portion 6 of the pipe is not unnecessarily obstructed.

The vents are preferably elongated in cross section and are arranged parallel, each being inclined from the horizontal as shown in Figs. 1 and 5. The end portions 11 of these vents, as shown in Fig. 4, widen outwardly in order to impart a fan-shape to the jets. The flushing discharge pipe 4, is positioned between the rear vehicle wheels, one end of the pipe extending in front of one rear wheel and the other end behind the other rear wheel, as shown in Fig. 2. Water is admitted to the conduits 3 by opening a suitable valve indicated at 12. In addition to the flushing pipe 4 a sprinkling device 13 is, in the construction shown, also provided.

The invention being intended to be defined solely by the claims, is not to be limited by details of construction shown or described.

I claim:

1. In a machine of the character described, a discharge pipe of uniform cross section throughout its length and having vents through its wall, the portions of the pipe's inner surface nearer the vents and on opposite sides thereof gradually and uniformly converging in the pipe's cross-sectional direction more closely to parallelism than portions of such inner surface more remote from the vents whereby the passage to the vents is gradually contracted.

2. In a machine of the character described, a discharge pipe having vents through its wall, the portions of the pipe's inner surface nearer the vents and on opposite sides thereof gradually and uniformly converging in the pipe's cross-sectional direction more closely to parallelism than portions of such inner surface more remote

from the vents, whereby the passage to the vents is gradually contracted, the pipe being horizontally disposed, and the vents being elongated in cross section and arranged parallel with each other and inclined from the horizontal direction of the pipe.

5 In testimony whereof I have hereunto set

my hand in presence of two subscribing witnesses.

WILLIAM C. INGRAM.

Witnesses:

CYRUS W. RICE,
HENRIETTA K. VANDER MYDE.
